UNITED STATES PATENT OFFICE.

ODUS A. BENEFIEL, OF RUSHVILLE, MISSOURI.

AUTOMATIC TRAIN-STOP.

1,206,657.

Specification of Letters Patent. Patented Nov. 28, 1916.

Application filed September 9, 1914. Serial No. 860,879.

To all whom it may concern:

Be it known that I, ODUS A. BENEFIEL, a citizen of the United States, residing at Rushville, in the county of Buchanan and State of Missouri, have invented certain new and useful Improvements in Automatic Train-Stops; and I do hereby declare the following to be a full, clear, and exact description of the invention, such as will enable others skilled in the art to which it appertains to make and use the same.

This invention relates to automatic train stops which embody electrical means controllable by the operation of a semaphore blade for closing an electrical circuit between electromagnets carried by an engine for automatically applying the air brake and cutting off the steam supply when the same endeavors to pass a semaphore which is set as a dangerous signal.

Another object of this invention is the provision of a short rail interposed within the railway track which is insulated from the electrically connected rails for preventing persons from accidentally stepping upon the two rails and short circuiting the electrical current.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views, and in which:—

Figure 1 is a view in side elevation of the improved automatic train stop showing the same applied to an ordinary locomotive and showing the semaphore and the connections therewith in perspective. Fig. 2 is a detail view in side elevation of the electrically operated mechanism for automatically cutting off the steam flow to the steam chest. Fig. 3 is a view in side elevation of the air brake operating mechanism, and Fig. 4 is a detail view in elevation of the means of making and breaking the electrical circuit upon the actuation of the semaphore blade. Fig. 5 is a plan view of the air brake operating mechanism.

Referring more particularly to the drawings, 1 designates an ordinary semaphore supporting post which has an ordinary sem-

aphore blade 2 carried by the upper end thereof, which semaphore blade is controlled in the ordinary manner from the signaling station. This semaphore blade is raised or lowered to indicate danger or safety for a train passing the semaphore. The semaphore blade 2 has a lever or rod 3 connected thereto, which extends downwardly along the exterior of the semaphore post and has its lower end loosely connected to an angled lever 4, which is pivoted at 5 or at the conjunction of the two arms, to a block 6 which is carried by the semaphore post 1. The angled lever 4 is pivotally connected at 7 to a bar 8, which bar is in turn pivotally connected at 9 to a lever 10. The lever 10 is pivoted intermediate its ends as at 11 to a block 12, which block is provided with an arcuate slot 13 in which is seated an enlarged head 14 formed upon the upper end of the lever 10. The head 14 is connected to an electrical conductor 15 which electrical conductor is connected to one pole of a battery, while the slot 13 has a contact 16 mounted therein which is connected through the medium of an electrical conductor 17 to the opposite pole of a battery or other suitable electrical supply source. The head 14 which forms the contact, is movable within the arcuate slot 13 for engagement with or movement out of engagement with the contact 16, depending upon the direction of the operation of the lever 10 and the bar 8. The head 14 and the contact 16 are electrically connected to one of the rails 18 of an ordinary railway track. The electrical supply source indicated by a battery 20 in Fig. 1 of the drawings is electrically connected to a rail 21, through the medium of a conductor 22. The rails 18 and 21 have interposed between their facing ends a short rail 23, which is insulated, by means of insulating plates 24, from the rails 18 and 21 so that it will be impossible for a person walking along the track to step upon the rails which are electrically charged and form a short circuit.

When the semaphore blade 2 is in a raised position for designating or indicating that there is danger for a train passing along the track, the contact head 14 engages the contact 16 and an electrical current passes through the rails 18 and 21 when a short rail 23 is bridged by a train. When the semaphore is lowered to indicate safety for the passage of a train the contact head 14 is

moved out of engagement with the contact 16 and the circuit is broken at this point.

The engine carried mechanism consists of the various parts which will be hereinafter more fully described. The front pilot wheel 30 of the engine is insulated from the axle 31 upon which it is mounted and it has a plate 32 secured thereto, which plate has an electrical conductor 31 electrically connected thereto. The electrical conductor 31 extends rearwardly along the side of the engine 33 and is connected to one terminal of the winding of the solenoids 34 and 35, which windings have their opposite terminals connected 15 to the rear track wheels 36 of the engine by an electrical conductor 37. The solenoid 34 has a central rod or armature 38 mounted therein which is insulated from the solenoid and has a plate 39 mounted thereupon, 20 which plate normally rests in spaced relation with one end 40 of the solenoid, so that when the solenoid 34 is energized the plate 39 will be attracted by the end 40, for forcing the rod 38 longitudinally. The rod 38 is pivotally connected to a lever 41, which lever is supported within the engine cab in any suitable manner. The lever 41 is pivotally connected to a rod 42, which rod extends out of the cab of the engine longitudinally beside the boiler, and has its outer end connected to an angled lever 43. The angled lever 43 is pivotally mounted at 44 upon the sides of the boilers of the engine 33, and it has a valve stem 45 connected to the end 35 of the arm which is free from connection with the rod 42. The valve stem 45 is associated with the valve (not shown) which is mounted in a valve casing 46, which casing is interposed in the steam connection between the steam chamber of the boiler of the engine and the steam chest 47, so that when the valve stem 45 is moved longitudinally, in the direction indicated by the arrow A in Fig. 2 of the drawings, the passage 45 of steam through the steam pipe 48 which leads to the steam chest 47, will be cut off.

The solenoid 35 has a rod 50 slidably mounted therein, which has a plate 51 mounted thereupon. The plate 51 is normally spaced from the end 52 of the solenoid so that when the solenoid 35 is energized, the magnetic attachment of the same will attract the plate 51 toward the end 52 of the solenoid, and move the rod 50 longitudinally 55 therein. The rod 50 is pivotally connected to a lever 53, which lever is in turn pivotally connected to a link 54. The link 54 has its end 55 reduced, which reduced end is seated between the arms 56 and 57 of the link 58. The link 58 is connected to the air brake controlling lever 59, so that when the rod 50 is moved longitudinally within the solenoid 35, and the lever 53, and links 54 and 58 are operated, the air brake controlling lever 59 will be operated for exhaust-

ing the air from the train line for setting the brakes on the train.

In the operation of the improved electrically operated automatic train stop: when the semaphore blade is set to designate danger, the head 14 is moved so that a circuit will be closed between the electrical supply source 20 and the rails 21 and 18 will be charged with the current from the opposite poles of the battery. When an engine moving along the track is moved so that the forward pilot wheel 30 will engage the rail 18 and the rear track wheel 36 will engage the rail 21, a circuit will be closed through the various electrical connections carried by the engine, which will energize both the solenoids 34 and 35, and synchronously cut off the supply of steam to the steam chest 47, and apply the air brake for instantaneously stopping the train.

In Fig. 1 of the drawings a modified form of the contact which is operable by the semaphore blade is shown. This modified form embodies a pair of plates 60 and 61 which are disposed in alignment with each other. The plate 61 is connected to the rail 18 by an electrical conductor 17', while the plate 61 is connected to the battery 20 by an electrical conductor 15'. The plate 61 is pivotally carried by the lever 62, which lever is connected through the medium of a link 63 and an angled lever 64 with the vertical rod 3 of an ordinary semaphore signal. Upon the actuation of the semaphore signal, the rod 62 which pivotally supports the plate 61 will be moved in an oscillatory manner for moving the plate 61 into or out of contact with the plate 64 closing a circuit for performing functions identical with the operation of the head 14 and the contact 16 heretofore described.

From the foregoing description taken in connection with the accompanying drawings the advantages of the construction and of the method of operation of the improved automatic train stop will be readily apparent to those skilled in the art to which this invention appertains and, while in the foregoing description, the principle of the operation of this invention has been described together with the various features of construction, it is to be understood that certain minor features of construction, combination and arrangement of parts may be altered to suit practical conditions provided such alterations are comprehended within the scope of what is claimed.

What is claimed is:

1. In combination with a locomotive provided with electrically controlled automatic stopping means and having the wheels of its pony truck insulated from the axle thereof, a pair of alining rails, the adjacent ends of said rails being spaced, said rails being adapted to carry electric current, a section

5 of rail insulated from and secured to the rails to form a substantially continuous rail and to prevent the rails from being electrically connected except when the locomotive bridges said rail and thereby causes the stop mechanism to be operated.

10 2. In a train stop, a locomotive provided with the usual steam dome, steam chest, pipe for connecting the steam dome and steam chest and a throttle valve for controlling the flow of the steam from the dome into the steam chest, a gate valve mounted in said pipe between the throttle valve and the steam chest, electrical means controlling the operation of said gate valve, an air valve, electrical means controlling the operation of the air valve, the steam and air valve controlling means being in series, wheels carried by and insulated from the pony truck of the locomotive, a wire leading from said wheels 15 to the steam valve controlling means, a wire connecting the steam valve controlling means with the air valve controlling means, a wire connecting the air valve controlling means to the frame of the locomotive, a pair of track rails in spaced relation and arranged in longitudinal alignment, a rail section of less length than the length of the locomotive connecting the rails and being 20 insulated therefrom, a power source, a wire connecting one terminal of the power source to one of the rails, an automatically operated switch, a wire connecting the opposite terminal of the power source to one pole

25 of said switch, a wire connecting the opposite pole of the switch with the other rail and means to close the switch upon the movement of a semaphore arm into its "danger" position.

3. In combination with a locomotive having electrically controlled stopping means, a pair of rails arranged in spaced longitudinal alignment, a section of rail connecting the rails, and insulated therefrom to form a substantially continuous rail, a semaphore 35 positioned near the rails, a semaphore arm at the upper end of the semaphore, a switch, one pole of said switch being connected to one of the rails, a power source, one terminal of the power source being connected to the opposite terminal of the switch, the opposite terminal of the power source being connected to the other rail and means connecting the semaphore arm with the switch whereby upon the movement of the 40 semaphore arm into "danger" indicating position, the switch will be closed, thereby charging both rails and causing the current to flow through the train stopping mechanism, when the locomotive bridges the rail 45 section.

50 In testimony whereof I affix my signature in presence of two witnesses.

ODUS A. BENEFIEL.
